(57) **CLAIM**

The ornamental design for a furniture unit, as shown and described.

DESCRIPTION

FIG. 1 is a front perspective view thereof with a right arm and corner configuration;

FIG. 2 is a rear perspective view of the embodiment of FIG. 1; FIG. 3 shows a front perspective view as in FIG. 1 with springs shown in environmental broken lines for illustration purposes only;

FIG. 4 shows a rear perspective of the embodiment shown in FIG. 3;

FIG. 5 is a front elevational view of the embodiment shown in FIG. 1;

FIG. 6 is a rear elevational view of the embodiment shown in FIG. 1;

FIG. 7 is a left side view of the embodiment shown in FIG. 1;

FIG. 8 is a right side elevational view of the embodiment shown in FIG. 1;

FIG. 9 is a top plan view of the embodiment of FIG. 1;

FIG. 10 is a bottom plan view of the embodiment of FIG. 1;

FIG. 11 is a front perspective view thereof with a left arm and corner configuration;

FIG. 12 is a rear perspective view of the embodiment of FIG. 11;

FIG. 13 shows a front perspective view as in FIG. 11 with springs shown in environmental broken lines for illustration purposes only;

FIG. 14 shows a rear perspective of the embodiment shown in FIG. 13;

FIG. 15 is a front elevational view of the embodiment shown in FIG. 11;

FIG. 16 is a rear elevational view of the embodiment shown in FIG. 11;

FIG. 17 is a left side view of the embodiment shown in FIG. 11;

FIG. 18 is a right side elevational view of the embodiment shown in FIG. 11;

FIG. 19 is a top plan view of the embodiment of FIG. 11; and, FIG. 20 is a bottom plan view of the embodiment of FIG. 11.
